UNITED STATES PATENT OFFICE.

FORD W. HARRIS, OF WILKINSBURG, PENNSYLVANIA, ASSIGNOR TO WESTINGHOUSE ELECTRIC & MANUFACTURING COMPANY, A CORPORATION OF PENNSYLVANIA.

SYSTEM OF ELECTRIC-MOTOR CONTROL.

No. 892,421.

Specification of Letters Patent.

Patented July 7, 1908.

Application filed September 5, 1905. Serial No. 277,103.

To all whom it may concern:

Be it known that I, FORD W. HARRIS, a citizen of the United States, and a resident of Wilkinsburg, in the county of Allegheny and State of Pennsylvania, have invented a new and useful Improvement in Systems of Electric-Motor Control, of which the following is a specification.

My invention relates to systems of electric motor control and particularly to systems which are adapted for starting relatively large motors.

The object of my invention is to provide a system for the purpose set forth, that shall embody a set of successively-closed switches of simple arrangement and construction; that shall be effective in operation and that shall automatically open a main circuit interrupting device if the switches of the set are closed in other than the regular predetermined order.

When relatively large electric motors are started by gradually reducing the resistance in series therewith it is desirable to effect this result by means of a plurality of switches which are closed in a predetermined order and which may be readily adapted for carrying and interrupting large currents without excessive heating or damage from arcing. In the prior art it has been usual to mechanically interlock switches of this nature to insure their closure in a predetermined sequence, but inasmuch as such interlocking means might be overcome by the application of sufficient mechanical force, it was possible to close the switches in such order as to so reduce the resistance that excessive currents would be supplied to the motor.

The arrangement of my invention does not prevent the closing of the switches in any order or combination, but provides means for automatically interrupting the motor circuit if they are closed in other than a predetermined, suitable order.

The single figure of the accompanying drawing is a diagrammatic view of my invention as applied to a single motor that is operated in one direction only. I desire it to be understood, however, that my invention may be applied to a motor which is adapted for running in either direction and that it may be otherwise modified as to number and arrangement of parts as well as in its application, if desired.

Referring to the drawing, electrical energy

is supplied from a line terminal 1 through a main line circuit-breaker 2 to a motor 3, which is provided with a suitable starting device 4, that regulates the amount of resistance which is connected in series with the motor. The circuit-breaker 2 is arranged in the usual manner to entirely disconnect the motor from the supply line and is provided with an overload release magnet 5 which serves to trip the breaker and open the circuit when the current supplied to the motor exceeds a predetermined value.

The starting device 4 comprises a plurality of switches 6, 7, 8, 9, 10 and 11 which may be so arranged and equipped as to be closed 70 either manually or otherwise and which may be provided with interlock relay switches 12, 13, 14, 15, 16 and 17. The system may also include a holding switch 18, which serves to prevent an attendant from leaving the starting device before all the switches are closed. Each of the switches 6, 7, 8, 9, 10 and 11 is provided with a retaining coil 19 which serves to hold its switch in closed position after it is moved to such position by the operator. 80 The interlock relay switches 12, 13, 14, 15, 16 and 17 are so connected and arranged, however, that the main motor circuit and the circuit through holding coils 19 are interrupted by a circuit-breaker 20, in case the 85 switches are closed in other than a predetermined order.

In starting the motor 3, the switch 18 is first moved to its closed position. The circuit-breaker 20 is then closed, which completes a circuit from the line terminal 1 through the contact members 21 of the circuit-breaker 2 and its overload coil 5, field magnet winding 22 and armature 23 of the motor 3, a series resistance 24, the circuit-breaker 20 and contact members 25 of the circuit-breaker 2 to an opposite line terminal 26.

The circuit-breaker 20 is normally held in its closed position by a holding coil 27, a circuit being completed, when the switches 6, 7, 8, 9, 10 and 11 are open and the switch 18 is closed, from the positive line terminal 1 through a conductor 28, switch 18, the contact members 29 and 30, 31 and 32, 33 and 34, 35 and 36 and 37 and 38 of the respective relay switches 17, 16, 15, 14 and 13 and through conductor 39, coil 27 of the circuit-breaker 20 and the contact members of circuit-breakers 20 and 2 to the line terminal 26. 110

As the switches 6, 7, 8, 9 and 10 are successively closed, resistances 40, 41, 42, 43 and 44 are successively connected in multiple with the resistance 24 and as the switch 5 11 is closed the conductor 46 is connected directly to the conductor 47, thereby short-circuiting all the resistances. Since each switch and its corresponding resistance is included between the conductors 46 and 47, 10 the latter of which is connected to the circuit-breaker 20, it is obvious that the circuit-breaker 20 must be closed next after the closing of the switch 18. After the circuit-breaker 20 has been closed, the switch 18 being held in closed position, the switch 6 may be closed, thereby connecting the resistance 15 40 in multiple with the resistance 24.

If any one of the switches 7, 8, 9, 10 and 11 is closed while the switch 6 is open, the 20 aforesaid circuit through holding coil 27 of the circuit-breaker 20 is interrupted and the circuit-breaker is automatically opened. After the switch 6 is closed, however, a circuit is completed from the terminal 37 of the 25 relay switch 13 through contact members 48 and 49 of the relay switch 12 so that the switch 7 may be closed without interrupting the circuit through the retaining coil 27. The closing of the switch 7 completes the circuit 30 from the contact member 35 of the switch 14 through contact members 50 and 51 of the relay switch 13, which are connected to the contact member 37, so that the switch 8 may now be closed without interfering with the circuit through the holding coil. The relay switches 14, 15, 16 and 17 are similarly and respectively provided with contact members 52—53, 54—55, 56—57 and 58—59, which are connected together 35 only when the corresponding main switches are closed. The connections through the relay switches 14, 15, 16 and 17, which will be readily understood from the description of the circuits through the switch 13, are such 40 that the circuit-breaker 20 will open if the switches 6, 7, 8, 9, 10 and 11 are closed in other than the order named.

When the switch 11 is closed a circuit is completed from conductor 28 through the 50 contact members 58 and 59 of the relay switch 17 so that the switch 18 may be opened without affecting the circuits already completed.

A gradual and suitable reduction of the 55 resistance in series with the motor to be started is effected by the means herein set forth and the attainment of full speed conditions is insured because the switch 18 must be held in a closed position by the attendant 60 until the resistance is short-circuited. In this way a resistance of relatively small capacity for continuous service, may be safely utilized for starting the motor since it may be kept under the observation of the attendant 65 during its entire period of service.

Specific illustration and description of a preferred embodiment of my invention are not to be so construed as to exclude equivalent means for effecting substantially the same result.

I claim as my invention:

1. In combination with an electric circuit, a plurality of independently - movable switches in said circuit, and means for automatically breaking said circuit upon the closing of said switches out of a predetermined order.

2. The combination with an electric circuit, a plurality of manually - operated switches therefor and means for automatically opening the circuit when said switches are closed in other than a predetermined order, of a controlling switch that must be manually held in its closed position until said switches are all closed.

3. In combination with an electric circuit, a plurality of independently-movable switches in said circuit, and means jointly controlled by said switches arranged to remain inoperative upon the closing of said switches serially in a predetermined order and to break said circuit automatically upon the closing of said switches out of said order.

4. The combination with an electric circuit, a plurality of manually-operated main switches therefor, and an electro-magnetic means for holding said switches in closed position, of a controlling switch that renders said holding means ineffective unless it is manually held in closed position until all of said main switches are closed.

5. The combination with a supply circuit, a dynamo-electric machine, a resistance therefor, and a plurality of switches that control the amount of the resistance included in circuit, of means for opening the main circuit of said machine when the switches are closed in other than a predetermined order.

6. The combination with a supply circuit, a dynamo-electric machine, and a plurality of manually-operated switches that successively introduce resistances in parallel relation, of an electro-magnetic means for holding each of said switches in closed position and means for opening the main circuit when said switches are closed in other than a predetermined sequence.

7. The combination with an electric circuit, and a plurality of manually-operated main switches therefor, of means for automatically opening the circuit when said switches are closed in other than a predetermined order, said means comprising a circuit-breaker having a retaining coil and a plurality of relay switches actuated by said main switches to determine the circuit connections for said retaining coil.

8. The combination with an electric circuit, a plurality of manually-operated main switches therefor, and means for automatic-

- ally opening the main circuit when said switches are closed non-sequentially, said means comprising a circuit-breaker having a retaining coil and a plurality of relay switches actuated by said main switches to determine the circuit connections for said retaining coil, of a controlling switch that must be manually held in closed position until the main switches are all closed.
9. The combination with an electric motor and a circuit-interrupting device connected in series therewith, of starting means for said motor that comprises a plurality of manually-operated switches and means for opening said circuit-interrupting device when the switches are closed in other than a predetermined order.
10. The combination with a supply circuit, an electric motor, an interrupting device for said circuit, a plurality of starting resistances for said motor, and means for adjusting their circuit connections in a regular order, of means for actuating said interrupting device to break the supply circuit when the circuit connections of the resistances are adjusted irregularly.
11. In an electric circuit, the combination with a plurality of switches adapted for closing in a predetermined order, of a circuit-breaker and means for tripping the same when any switch is closed in other than its proper order.
12. The combination with an electric circuit, and a plurality of switches therefor that are constructed and arranged to be closed in a predetermined sequence, of means for automatically opening the main circuit with which said switches are connected whenever any switch is closed non-sequentially.
13. The combination with a supply circuit, a dynamo-electric machine and a starting resistance therefor, of a plurality of switches for varying said resistance and means for automatically interrupting the supply circuit when any switch is closed non-sequentially.
14. The combination with a main circuit and a variable resistance therefor, of a plurality of switches adapted and arranged for progressively varying said resistance, and means for automatically opening the main circuit whenever any switch is closed non-sequentially.
15. The combination with a main circuit and an interrupting device therefor, of a resistance, a plurality of switches connected and arranged for sequential operation to progressively vary the effective amount of said resistance and means for automatically tripping the circuit interrupter when any switch is closed non-sequentially.
16. In combination with an electric circuit, a plurality of independently-movable switches in said circuit, an electro-magnet, and means controlled by said electro-magnet for automatically breaking said circuit upon the closing of said switches out of a predetermined order.
17. In combination with an electric circuit, a plurality of switches in said circuit, a no-voltage release device operatively connected to one of said switches, and contacts controlled by the other switches controlling said device.
18. In combination with an electric circuit, a plurality of switches in said circuit, a no-voltage release device operatively connected to one of said switches, and means for deenergizing said device upon the closing of the other switches out of a predetermined order.
19. In combination with an electric circuit, a plurality of switches in said circuit, a no-voltage release device operatively connected to one of said switches, and switch-contacts controlled by the other switches arranged to break the circuit of said device upon the closing of said switches out of a predetermined order.
20. In combination with a rheostat, a plurality of mechanically-independent switches controlling the resistance thereof, and means for automatically breaking the circuit of said rheostat upon the closing of said switches out of a predetermined order.
21. In combination with a rheostat, a plurality of mechanically-independent switches controlling the resistance thereof, an electro-magnet jointly controlled by said switches, and means controlled by said magnet for automatically breaking the circuit of said rheostat.
22. In combination with a rheostat, a plurality of mechanically-independent switches controlling the resistance thereof, a no-voltage release device, and contacts controlled by said switches and controlling said device.
23. In combination with a rheostat, a plurality of mechanically-independent switches controlling the resistance thereof, a no-voltage release device, and contacts controlled by said switches and arranged to break the circuit of said device upon the closing of said switches out of a predetermined order.
24. In combination with an electric circuit, a plurality of independently-movable switches in said circuit, an electro-magnet, means controlled by said magnet for breaking said circuit when the magnet is deenergized, contacts controlled by said switches for deenergizing said magnet upon the closing of said switches out of a predetermined order, and a normally open switch in circuit with said magnet and arranged to be short-circuited by the closing of the last of the first-named switches.
25. In combination with an electric circuit, a plurality of independently-movable switches in said circuit, an electro-magnet,

means controlled by said magnet for breaking said circuit when the magnet is deenergized, contacts controlled by said switches for deenergizing said magnet upon the closing of said switches out of a predetermined order, and a switch arranged normally to energize said magnet and to be rendered inoperative by the closing of the last of the first-named switches.

In testimony whereof, I have hereunto subscribed my name this 29th day of August, 1905.

FORD W. HARRIS.
